TRANSPORT EQUIPMENT FOR HIGHWAY
CONSTRUCTION MACHINES AND THE
LIKE

Robert D. Baker, Birmingham, Mich.

Application January 11, 1932. Serial No. 585,839

6 Claims. (Cl. 37—108)

This invention has for its object to provide simple and efficient means for effecting removal or transportation of certain types of machinery used in the highway construction art, such as fine-grading machines, pavement finishing machines and the like, which, when in use, travel upon the side-forms bordering the pavement strip.

Machines of the aforesaid type are very short from front to rear in order that they may be carried on a conventional highway trailer or flat-car from place to place without being taken apart, in whole or in part, and without projecting and extending at any point beyond the side edges of such flat-cars or trailers and without violating State highway ordinances as to width, etc.

The width of machines of this type is such that they span the side-forms bordering the pavement strip and project in part beyond one or both of the said forms. The width of such pavement strips varies from eighteen to twenty-four feet.

The frames of such machines are usually constructed of conventional steel units, such as I-beams, channel bars, angle irons or equivalents thereof. These units are more or less flexible and, therefore, are subject to distortion under certain conditions such as are hereinafter particularly pointed out.

In practice, these machines each weighing several tons, must be transferred from flat-car or highway trailer to side-forms at place of work and back to flat-car or trailer after completion of the work. During progress of the work, it is quite frequently necessary to move the said machine to one side of the pavement strip and, in many instances, from one location to another where freight car transportation is not available.

Each removal of the machine involves its removal from and replacement upon the side-forms and must be accomplished without disturbing the latter. Removals to and from freight cars and from one location to another also involve travel over very rough ground.

To load such machines upon automotive trucks for transport involves great labor because of the weight and bulk of the machines and is laborious and time consuming.

Therefore, it has been customary heretofore to provide each machine of the several aforesaid types with axle elements at substantially the balance point between the sides of the machine for receiving wheels of suitable diameter upon which said machines are supported in transit.

To mount the said wheels upon said axle elements, it is necessary first to jack-up one or both sides of the machine to a very appreciable elevation above the side-forms, then slip the wheels upon the axle elements and lower the machine until its weight is borne by said wheels, the axis of the latter being parallel with the sides of the machine.

The machine may now be swung upon a vertical axis or it may be moved laterally and then swung around and may also be carried on said wheels to a distant location. When so carried, the said wheels will pass over somewhat uneven surfaces even though traveling on pavement and this will cause flexing and springing of the machine frame during such travel and generally causes the frame members to become more or less bent and distorted because they are supported only in the vertical plane of the axis of said wheels. Such bending or distortion of frame members may not be visibly perceptible but is reflected in disalignment of bearings and consequent binding of shafts, hot-boxes, and burning out of bearings; loss of power; breakages; and the like.

The last-mentioned results are, of course, very serious. The matter of time required to apply and remove the transporting wheels is also a matter of serious moment because delay in this operation may readily cause similar delay in other operations and thus cause appreciable loss.

The main object of the present invention is, therefore, to provide transporting equipment for machines of the types indicated which is easily and quickly applied and includes means for raising the machine after the wheels are applied; which will also support the machine during travel on said wheels so as to prevent distortion of frame members and other parts; and which do not require the inclusion of heavy axle elements as part of the machine frame to add to the weight of the latter.

A suitable embodiment of the invention is illustrated in the accompanying drawings, wherein:

Fig. 1 is a front elevation of a fine-grading machine supported on a transporting equipment constructed in accordance with the invention.

Fig. 2 is a central vertical section of the transporting equipment per se, taken on an enlarged scale on the line 2—2 of Fig. 1, some of the frame members of the machine to be elevated being also shown in normal position prior to elevating the same.

Fig. 2a is a view similar to Fig. 2, showing the machine frame in elevated position.

Fig. 3 is a vertical sectional view of the transporting equipment taken on the line 3—3 of 5 Fig. 2a.

Fig. 4 is a fragmentary detail vertical section taken on the line 4—4 of Fig. 1.

Fig. 5 is a detail fragmentary plan section taken on the line 5—5 of Fig. 2a.

10 Fig. 6 is a fragmentary plan section taken on the line 6—6 of Fig. 1, illustrating draft-gear detachably secured to one side of the machine.

Fig. 7 is a vertical sectional view taken on the line 7—7 of Fig. 6.

15 Fig. 8 is a vertical sectional view taken on the line 8—8 of Fig. 6.

In the drawings I have shown the type of machine illustrated and described in my application for Letters Patent of the United States, Serial 20 No. 488,734, filed October 15, 1930, as exemplary of the general class of machines to which my invention particularly applies without, however, limiting the use thereof as applied to other machines. Other machines to which the present 25 invention may be advantageously applied are illustrated in United States Patents Nos. 1,653,333; 1,522,128; and others, provided at the sides thereof with wheels 1 traveling on the side-forms 2 of a pavement strip 3, when in use.

30 The said wheels 1 or the side trucks in which they are mounted and which they carry, support the transverse frame elements of the machine, exemplified in the instant case by the channel bars 4, 5, and 6, which span the strip 3 and carry a part of the operating mechanism or mechanisms of the respective machines. Said machines are usually equipped with an engine 7 at one side and, generally speaking, have the parts of greatest weight disposed at or adjacent 35 the sides of the frame or carriage because the latter is obviously less flexible than the portions thereof disposed inwardly of the side-forms 2. The said members 4, 5, and 6 are spanned by a connecting bar 5^a secured thereto. Obviously, 40 the middle portion of the frame is designed to be supported by the side portions which, in turn, are supported upon the side-forms so that, in suspending the machine from the axis of the wheels of transporting equipment, the distribution 45 of weight is the reverse with consequent danger of frame distortions, etc., as hereinabove pointed out. Furthermore, in its travel on the side-forms, the machine follows a path smoother than the best pavement, while in travel, when 50 carried by the said equipment, it is subjected to jars, shocks and vibrations which cannot be taken into account in designing the machine frame because of the additional weight involved. Weight must be minimized because of the limit 55 of carrying power of the side-forms when disposed upon soft earth to prevent sinking thereof, and also to facilitate transport and handling of the machine.

The invention, therefore, consists in providing 60 a pair of what I term "bridge-members" 8, each consisting of an inverted channel bar having the end portions of its web cut away to leave the end portions of its flanges free. The said flanges terminate in vertically disposed extremities. In 65 the instance illustrated, the said bridge-members 8 are arcuate and, by reason of cutting away the end portions of the webs thereof, are provided at their ends with recesses bordered by the end portions 9 of the flanges in which the frame members 4 and 6 are received. The extremities of

the flanges are provided with openings to receive the bolts 10 which underlie the said frame members 4 and 6. The said frame members 4 and 6 are equipped with stop members 10^a for engagement by bolts 10 to prevent movement of the ends of the bridge or truss members 8 responsively to flexing thereof under the influence of the weight of the machine.

Each bridge member 8 is provided at its middle portion with a bearing 11 for the smooth end portion of a screw-shaft 12 which also passes through an opening in the web of the bridge member 8. Said screw-shaft 12 is equipped with collars 13 and 14 to confine it against longitudinal movement relatively to said bearing 11 and is also equipped with a square end portion 15 to receive a wrench or other device for rotating the screw-shaft.

An axle 16, the middle portion of which is composed of a pair of parallel channel bars having their webs vertically disposed and having the edges of their respective flanges opposed but spaced apart, is equipped at its ends with the stud-shafts 17 upon which the transport wheels 18 are rotatably mounted. The said stud-shafts 17 are integral with the square end portions 19 disposed between the channel bars of the axle 16 and are rigidly secured thereto.

95 Each of the said square end portions 19 is equipped with a threaded bushing 20 in which a screw-shaft 12 engages.

The frame members 4 and 6 are provided at substantially the balance point between the sides of the machine, with a pair of parallel angle irons or other equivalent stop elements 21 between 100 which the axle 16 is received and held against lateral movement.

The diameter of the wheels 18 is somewhat more than twice the maximum elevation of the tops of the frame members 4 and 6 above the grade 115 or earth surface over which the machine is disposed in use and travel. As the side-forms of different pavement strips differ in height from a minimum of six inches to a maximum of ten inches, the frames of fine-grading machines and possibly other machines, are equipped with means for raising and lowering the said frames relatively to the axes of their wheels in order to dispose the operating mechanisms of the said machine in the desired plane determined by the crowns 120 and bases of the side-forms. In the instance of the machine illustrated in Fig. 1, the elevation of the tops of the frame members 4 and 6 above the plane of operation of the grade cutting devices 22 will approximate twenty-one inches. Hence, in 130 this instance, the diameter of the wheels 18 will be no less than fifty inches in order to provide several inches of clearance between the lowest portions of the operating mechanism and the ground during transport of the machine.

In use, the axle 16 may be initially disengaged from the screw-shafts 12 so that each bridge element 8 may be mounted on a frame member 4 or 6 independently of the other for ease in handling by one person, if desired, or if, as is usual, a number of men are available, the said axle 16 is maintained engaged with said screw-shafts 12 and the assembly, consisting of both bridge members 8, said screw-shafts 12, and axle 16, is then mounted upon the frame members 4 and 6 with the axle 140 disposed in vertical alignment and appreciably higher than the stop elements 21.

145 The wheels 18 are then mounted on the said stud-shafts of the axle 16 and the screw-shafts 12 are then rotated in a direction to raise the bridge- 150

members, which are attached to members 4 and 6, thus also raising the machine until the axle is in close contact with the members 4 and 6 and is disposed between the stop formations 21. This action brings the machine side-wheels 1 clear of and well above the side-forms to the position shown in Fig. 2a, so that the machine now may be pulled in any desired direction.

It will be noted that the frame members 4 and 6 are now suspended from the bridge-members 8 at points so near to the sides of the machine as practically will prevent flexing of the said frame members and limit such flexing, if any, to such a small degree as will prevent permanent distortion of the same. It is also obvious that the middle portions of said frame members lying between their points of suspension or support are prevented from flexing by the counter pressure of the axle 16 and that this rigidity of the middle portions of said frame members renders the outer end portions thereof far more rigid.

My said transport equipment is also advantageous in that it is applied without requiring the punching or drilling of holes in the frame members 4 and 6 or securing devices thereto other than the stop members 10^a and 21, by means of which attachment to the transport equipment is effected.

When said transport equipment is applied to the machine for the purpose of disposing the same at one side of the pavement strip in order that material trucks may pass, enroute to the paving material mixer, a few men can easily and quickly effect such moving.

When, however, the machine is to be transferred to a distant point, it is coupled to a tractor or truck by means of a suitable draft-rig, such as, for example, is shown in Figs. 6 to 8, inclusive, wherein the frame members 4 and 6 are equipped with straps 23 provided in their projecting end portions with openings in which is received the shaft 24 which also passes through openings in three draft elements 25 and 26 at the rear end of the tongue structure 27 of V-shape which is equipped at its apex with the coupling loop 28. The draft elements 26 are bolted to vertically disposed angle iron frame members 29 of the machine in the instance illustrated which happen to be conveniently located for this purpose. The frame members 29 cooperate with the shaft 24 to prevent pivotal movement of the tongue structure 27 on a horizontal axis and thus prevents the machine from swinging on the axis of the axle 16 during travel, the loop 28 being so coupled with the tractor or truck as to hold it against vertical movement relative to such vehicle.

Cotter pins 30 hold the shaft 24 against longitudinal movement.

My said transport equipment is very efficient and possesses the several advantages above pointed out with respect to preventing distortion of the machine frame and with respect to the short time required to attach the same to and detach it from the machine. It is also very simple and cheap, and possesses the further advantage of constituting an entirely separate and distinct unit which is absolutely independent of the machine except when mounted thereon, except as to the very light stop elements 21. It is also advantageous in that it includes the lifting jacks (screw-shafts 12) and thus obviates the presence and use of a lifting jack or the incorporation of lifting mechanism in the machine to be transported.

The screw-shafts or jack-screws 12 serve a

double purpose, one being to lift the machine, and the other being to clamp the axle down upon the frame members 4 and 6 for coaction with the supports for said members to render the same rigid.

I claim as my invention:

1. A transport equipment for the purpose specified including an axle adapted to be disposed transversely of and over frame members of a machine, a pair of wheels of a radius greater than the height of the said frame members disposed upon and supporting said axle initially at an elevation above the frame, a pair of supporting members overhanging said axle at points substantially midway between their ends, means at the ends of said supporting members for detachably securing the same to the said frame members at points spaced from the said axle, and vertically disposed jackscrews engaged with said axle and said supporting members and adapted to be rotated to raise and lower said supporting members relatively to the said axle for causing said frame to be raised and lowered relatively to the said axle and to cause the latter to bear upon the frame when the latter has been raised to prevent flexing of the frame members.

2. A transport equipment for the purpose specified comprising a pair of parallel supporting members each adapted to be secured at its ends to a frame member of a machine and disposed in overhanging relation between its ends to said frame member, a member extending transversely of said supporting and frame members and overlying said frame members and underlying the middle portions of said supporting members, means for attaching wheels to said transversely extending member, and means on said supporting members for raising and lowering said transversely extending member and clamping the same down upon the said frame members to prevent flexing of the latter.

3. A lifting and transport equipment for machines of the type specified comprising a truss element, means for engaging the ends of the truss element underneath the machine frame, a wheeled member disposed over said frame between the ends of the truss element, and mechanism engaged with said wheeled member and said truss element for raising the latter and said frame relatively to the wheeled member, said mechanism adapted to cause the wheeled member to bear upon the top of the frame for coaction with the truss element to prevent flexing of said frame.

4. A lifting and transport equipment for machines of the type specified comprising a truss element, means for engaging the ends of the truss element underneath the machine frame, a member rotatable relatively to said truss element and engaged with the same and with the top of the machine frame between the ends of said truss element, and a wheeled member engaged with said rotatable member for raising and lowering said truss element and machine frame by rotation of said rotatable member, the latter coacting with said first-named means to prevent flexing of the machine frame.

5. A transport equipment of the type set forth comprising a wheeled truck, a plurality of substantially inflexible tension members overhanging said truck between the wheels thereof, means for detachably securing said tension members to the frame of a machine to be transported for initial support by the latter, and manually operable mechanism engaging said truck and said

tension members between the ends of the latter for raising and lowering said tension members relatively to said truck while said tension members are secured to said machine frame, said mechanism adapted to cause the machine frame to be clamped to the underside of said truck as said frame attains the upper limit of its movement relatively to the said truck.

6. A transport equipment of the type specified, comprising a pair of parallel truss members, means at the ends of said truss members for securing the same to frame members of a machine to be transported, a bearing for the smooth end of a screw-shaft mounted upon the middle portion of each truss member, a screw-shaft jour-

nalled in each of the bearings, collars on said screw-shafts for preventing their longitudinal movement relatively to the said bearings, an axle having spaced apart threaded openings engaged with the said screw-shafts, means for engaging the said axle against lateral movement relatively to the frame of the machine to be transported as said axle is engaged with the said frame by rotation of the screw-shafts in one direction to cause said axle to bear upon the said frame, and wheels on said axle for supporting the latter at an elevation higher than the points in the machine frame engaged thereby.
